UNITED STATES PATENT OFFICE.

FREDERICK JAMES PARKS, OF CLEVELAND, OHIO.

DUPLEX ENVELOPE.

Application filed September 22, 1924. Serial No. 738,991.

My invention relates to envelopes and particularly to duplex envelopes adapted for containing mail matter of two different classes. More particularly, the invention relates to duplex envelopes having one pocket which may be sealed to carry first-class matter and a second pocket in which cheaper class matter is carried. The cheaper class matter is carried in an accessible pocket portion of an improved duplex envelope of the self-clasp type. One form of this self-clasp envelope, as a single envelope, is patented to me by U. S. Patent No. 1,459,414. One type of machine for automatically manufacturing said self-clasp envelope is illustrated in my U. S. Patent No. 1,316,737; and an improved process for manufacturing said self-clasp envelope having an automatically and detachably interlocked retaining pocket and closure flap is patented to me by U. S. Patent No. 1,459,415. The improved duplex envelope forming the subject-matter of this application is manufactured from a blank designed to be automatically operated upon in the manner described and claimed in said process Patent No. 1,459,415.

The annexed drawing and the following description set forth in detail certain means embodying my invention, such means disclosing, however, but one of the various forms in which the principle of the invention may be applied.

In said annexed drawing:

Figure 1 is a plan view of the blank from which the illustrated form of my improved duplex envelope is made;

Figure 2 is a view illustrating the state of the blank shown in Figure 1 after the completion of the initial folding thereof;

Figure 3 is a view illustrating the form of said blank after the completion of the second folding thereof, showing the first step in the formation of the flap-receiving pocket formed adjacent the mouth of the envelope which is adapted to receive the cheaper class mail matter; Figure 3 also shows the folding of the blank to form a pocket for receiving first-class mail matter, or other matter, if it is not desired to seal the last-named pocket.

Figure 4 is a view illustrating the form of said blank after the completion of said flap-receiving pocket and the interlocking of the closure flap therewith, the blank then being ready to receive the gum by means

of which certain blank side flaps are secured to the body portion to close the lateral edges of the two pockets adapted to receive the two kinds of filling material; 60

Figure 5 represents the blank shown in Fig. 4 after applying the gum for sealing the side flaps;

Figure 6 represents a view of the completed envelope, said blank side flaps having been folded over and secured in part to that portion of the envelope having a pocket for cheaper class mail matter, in part to the blank portion forming one wall of the pocket for receiving first-class mail matter, 70 and in part to the above-mentioned flap-receiving pocket, certain lateral tabs, hereinafter fully described, having also been folded over and secured beneath said side flaps in part to said flap-receiving pocket 75 and in part to said blank portion forming one wall of the pocket for receiving the first-class mail matter; and

Figure 7 represents, upon an enlarged scale, a longitudinal section, taken in the plane indicated by the line VII—VII, 80 Fig. 6.

Referring to the annexed drawing in which the several parts are indicated by the same respective ordinals in the different views, I show in Figure 1 a blank from which my improved envelope is made, the same having substantially rectangular front and back plies or portions 1 and 2 integrally joined in a transverse plane 3, joining edge 90 3 forming a permanent closure along that edge of the completed envelope which shall serve as the bottom of the pocket designed to receive the cheaper class mail matter. One of the plies 1 and 2, as for example the 95 ply 1, is wider than the ply 2, due to integral side flaps or extensions 4, formed along the opposite lateral side edges, these side flaps 4 being adapted to be folded over behind and sealed down upon corresponding lateral edge portions of other blank parts, hereinafter fully described, so as to afford permanent closures along the opposite lateral edges of both the pockets of the completed envelope which are adapted 100 to receive the first-class mail matter and the cheaper class mail matter, respectively.

The free edge of the front ply 1 is adapted to be triple folded along the lines 11, 12 and 13 to form a closure flap adapted to 110 be detachably interlocked in doubled form with a two-ply pocket formed by double

folded parts 5 and 6 of the back ply 2, said double folded parts 5 and 6 being positioned intermediate the ends of the back ply 2. The formation of the double ply pocket 5 and 6 and the closure flap automatically detachably interlocked therewith is shown in Figure 4 and is accomplished by the process patented to me by said U. S. Patent No. 1,459,415, in machines of which one type 10 is illustrated in my said Patent No. 1,316,737. As also fully described and shown in said Patent No. 1,459,415, the blank formation is such as to align the section 10 of the back ply 2 with the section 11 of the front 15 ply 1 to form an envelope mouth, said mouth furnishing an entrance to a pocket for cheaper class mail matter, in the duplex envelope herein shown and described.

20 In the form of blank shown in Figure 1, I have extended the back ply 2 to form a free end portion 15 having an extreme terminal edge portion 16, for the purpose now to be described. When the blank is subjected to its second folding operation to produce the form shown in Figure 3, the member 15 of the back ply 2 has been folded back and down upon the closed end part of said back ply to form the walls of a pocket 25 for first-class mail matter. This pocket for the first-class mail matter is sealed along the lateral edges by the side extensions 4 of the front ply 1 when said extensions 4 are folded back over and upon the rear of the back 30 ply 2, as plainly shown in Figure 6.

The wall member 15 of the first-class mail pocket is formed with a window 20 adapted to display the address of the mail receiver placed upon the pocket contents, as is well 40 understood, and the extreme terminal part 16 of said member 15 is scored along a line 18, and adapted to be sealed upon the member 2 to close the pocket containing the first-class mail matter. The said terminal part 45 16 is preferably provided with adhesive 17, as plainly shown in Figure 2, or the same may be applied by the user, as desired. In order that the first-class mail matter may 50 be readily accessible, the member 15 is formed with multiple perforations along the line 18, end notches 19 being formed in the member 15 whereby an envelope opener may be readily applied.

55 In order to join the two-ply pocket 5 and 6 securely to the envelope body, I form side tabs 14 upon the back ply 2 adjacently forward of the mouth line 10, as plainly shown in Figure 1, said side tabs 14 being adapted 60 when the blank is folded into the form shown in Figure 4, to overlap the double ply portion 5, and the blank portion 15, so that when the side flaps 4 are turned over and sealed down by means of the gum 21, said tabs 14 assume the position shown 65 plainly in Figure 6, the adhesive 21 spread-

ing enough to seal the flaps 4 to the portion 5. It is evident from an inspection of Figure 6 that the side flaps 4 are folded back and secured to the closed end of the blank portion 2 adjacent the edge 3 and also secured to the free end of said blank portion 2 formed by the part 15. The side tabs 14 are secured to the free end portion 15 and the edges of the pocket flap. The manner of the application of the gum 21 to the envelope blank in the form shown in Figure 4, so as to create the conditions shown in Figure 5, is fully described in my said Patent No. 1,459,415 and is also plainly shown and described in my pending application Serial No. 668,290.

70 It will be evident from an inspection of Figures 1 and 5 that the flap sections 7, 8 and 9 are so tapered toward the free end of the blank portion 1 that, when the side flaps 4 are folded over and sealed to form lateral closures, the sealed portions of said lateral flaps 4 do not extend inwardly as far as the adjacent portions of the flap section 7. Therefore, flap portion 7 is not 75 sealed down by the side flaps 4 but is free to be removed from the flap-receiving pocket, for the reception of the desired filler of cheaper class matter, for postal inspection, etc., together with the other flap sections 8 80 and 9, by a pull upon the terminal edge of said flap section 9.

85 It will be evident that the completed envelope will be furnished to the user in the form shown in Figure 6, the terminal portion 16 not being sealed but ready for sealing, either through the medium of adhesive 17 or by adhesive applied for the purpose by the user, if first class mail matter is carried, so soon as the first-class mail matter 90 has been inserted in the pocket immediately under the member 15.

95 If the filler pocket formed under the member 15 is utilized for unsealed matter, such as circular correspondence, etc., the terminal member 16 would not be provided with adhesive, but would be tucked in the pocket around the filler to retain the latter, as will be readily understood.

100 What I claim is:

105 1. A duplex envelope formed from a blank, said blank consisting of a rectangular portion of which a part intermediate its ends is to be double folded, the free end of said portion being folded back upon the opposite end of said portion which is beyond said double folded part, said rectangular portion being connected to a wider second portion having side edges to be 110 creased and folded and whose free end is to be triple creased and folded, said envelope having said two portions folded upon one another, a two-ply pocket flap formed on said first-named portion from said double 115 folded part to form a pocket adjacent the 120

115

120

125

130

mouth of the envelope, side flaps formed along opposite sides of said second-named portion and folded back and secured to the side edges of both ends of the first-named portion, and a three-ply closure flap formed on the free end of said second-named portion and folded over said pocket flap and detachably interlocked in doubled form in said pocket.

10 2. A duplex envelope formed from a blank, said blank consisting of a rectangular portion of which a part intermediate its ends, is to be double folded, the free end of said portion being folded back upon the opposite end of said portion which is beyond said doubled folded part, means for sealing said free end to the opposite end of said portion, said rectangular portion being connected to a wider second portion 15 having side edges to be creased and folded and whose free end is to be triple creased and folded, said envelope having said two portions folded upon one another, a two-ply pocket flap formed on said first-named portion from said double folded part to form a pocket adjacent the mouth of the envelope, side flaps formed along opposite sides of said second-named portion and folded back and secured to the side edges 20 of both ends of the first-named portion, and a three-ply closure flap formed on the free end of said second-named portion and folded over said pocket flap and detachably interlocked in doubled form in said pocket.

35 3. A duplex envelope formed from a blank, said blank consisting of a rectangular portion of which a part intermediate its ends is to be double folded, the free end of said portion being shorter than the opposite end which is beyond said double folded part and being folded back upon said opposite end, said rectangular portion being connected to a wider second portion having side edges to be creased and folded and whose free end is to be triple creased and folded, said envelope having said two portions folded upon one another, a two-ply pocket flap formed on said first-named portion from said double folded part to form a pocket adjacent the mouth of the envelope, side flaps formed along opposite sides of said second-named portion and folded back and secured to the side edges of the free end of said first-named portion, the remainder of said side flaps being folded back and secured to the side edges of the opposite, closed end of said first-named portion, and a three-ply closure flap formed on the free end of said second-named portion and folded over said pocket flap and detachably interlocked in doubled form in said pocket.

40 4. A duplex envelope formed from a blank, said blank consisting of a rectangular portion of which a part intermediate its ends is to be double folded, side tabs formed on

said portion adjacently forward of said double fold, the free end of said portion being folded back upon the opposite end of said portion which is beyond said double folded part, said rectangular portion being 70 connected to a wider second portion having side edges to be creased and folded and whose free end is to be triple creased and folded, said envelope having said two portions folded upon one another, a two-ply 75 pocket formed adjacent the mouth of the envelope on said first-named portion from said double folded part, side flaps formed along opposite sides of said second-named portion, said side flaps being folded back and secured to the side edges of both the free and closed ends of said first-named portion and to said pocket flap and said side tabs being folded back and secured to the corresponding edges of said free end and said 80 pocket flap, said side flaps covering said side tabs, and a three-ply closure flap formed on the free end of said second-named portion and folded over said pocket flap and detachably interlocked in doubled form in said 85 pocket.

5. A duplex envelope formed from a blank, said blank consisting of a rectangular portion of which a part intermediate its ends is to be double folded, the free end of said portion having a narrow terminal part and being folded back upon the opposite end of said portion which is beyond said double folded part, gum secured transversely of said free end adjacent the extreme edge thereof, transverse perforations formed in said free end adjacent to, and inwardly of, said gum, said free end being formed with a window, said rectangular portion being connected to a wider second portion having side edges to be creased and folded and whose free end is to be triple creased and folded, said envelope having said two portions folded upon one another, a two-ply pocket flap formed on said first-named portion from said double folded part to form a pocket adjacent the mouth of the envelope, side flaps formed along opposite sides of said second-named portion and folded back and secured to the side edges of both the free and closed end of said first-named portion, and a three-ply closure flap formed on the free end of said second-named portion and folded over said pocket flap and detachably interlocked in doubled form in said pocket.

6. A duplex envelope formed from a blank, said blank consisting of a rectangular portion of which a part intermediate its ends is to be double folded, the free end of said portion being folded back upon the opposite end of said portion which is beyond said double folded part, said free end being formed with a terminal member narrower than the body portion of said end, said rectangular portion being connected to a wider 125

second portion having side edges to be creased and folded and whose free end is to be triple creased and folded, said envelope having said two portions folded upon one another, a two-ply pocket flap formed on said first-named portion from said double folded part to form a pocket adjacent the mouth of the envelope, side flaps formed along opposite sides of said second-named portion and folded back and secured to the

side edges of both the free and closed ends of said first-named portion, and a three-ply closure flap formed on the free end of said second-named portion and folded over said pocket flap and detachably interlocked in 15 doubled form in said pocket.

Signed by me this 18th day of August 1924.

FREDERICK JAMES PARKS.
